Primary Examiner — Brian N. Vinson(74) *Attorney, Agent, or Firm* — Marshall, Gerstein & Borun LLP(57) **CLAIM**

The ornamental design for a lighting fixture, as shown and described.

DESCRIPTION

FIG. 1 is a bottom perspective view showing an example of a new design for a lighting fixture;

FIG. 2 is a bottom view of the lighting fixture of FIG. 1; and, FIG. 3 is a vertical, cross-sectional, perspective view of the lighting fixture of FIG. 1 taken through the exact center and in the direction of the rear of the lighting fixture.

The portions of the drawings illustrated in broken lines are for illustrative purposes only and form no part of the claimed design.

1 Claim, 3 Drawing Sheets(56)
